United States Patent Office

Des. 192,022
Patented Jan. 9, 1962

192,022

DRESS

Velia Marinelli, 1422 Post Ave., Rockford, Ill.

Filed Oct. 13, 1960, Ser. No. 62,480

Term of patent 14 years

(Cl. D3—26)

Fig. 1

Fig. 2

Fig. 3

FIG. 1 is a developed front view of a dress showing my new design, the train portion being omitted for convenience of illustration;

FIG. 2 is a developed rear view, and

FIG. 3 is a side view as the dress appears in wearing position.

The drawing has been lined for color.

I claim:

The ornamental design for a dress, substantially as shown and described.
